DESIGN FOR A DOOR MAT

Clarence E. Bauer, Norwalk, Conn., assignor to Danbury Rubber Co., Inc., Danbury, Conn., a corporation of Connecticut

Application April 2, 1947, Serial No. 138,113

Term of patent 14 years

(Cl. D9—6)

To all whom it may concern:

Be it known that I, Clarence E. Bauer, a citizen of the United States, residing at Norwalk, in the county of Fairfield, and State of Connecticut, have invented a new, original, and ornamental Design for Door Mats, of which the following is a specification, reference being had to the accompanying drawing, forming part thereof.

In the drawing:

I claim:

The ornamental design for a door mat, as shown,

CLARENCE E. BAUER.
